RIFLE

George A. Beck and Roy R. Bradbury II, Manlius, N.Y., assignors to Oy Sako AB, Ruhimaki, Finland, a corporation of Finland

Filed Aug. 31, 1964, Ser. No. 81,514

Term of patent 7 years

(Cl. D30—1)

We claim:

The ornamental design for a rifle, substantially as shown.
